Prindle and Russell, her Atty.

UNITED STATES PATENT OFFICE.

RACHEL LINDSLEY, OF WASHINGTON, DISTRICT OF COLUMBIA, ASSIGNOR
TO HELEN D. PAYN, OF SAME PLACE.

DESIGN FOR A BRUSH.

SPECIFICATION forming part of Design No. 30,663, dated May 2, 1899.

Application filed April 4, 1899. Serial No. 711,745. Term of patent 14 years.

To all whom it may concern:

Be it known that I, RACHEL LINDSLEY, a citizen of the United States of America, residing at Washington city, in the District of Columbia, have invented and produced a certain new and original Design for a Brush; and I do hereby declare that the following is a full, clear, and exact description thereof, reference being had to the accompanying drawings, in which—

Figure 1 is a perspective view of a brush embodying my design, and Fig. 2 a side elevation thereof.

Letters of like name and kind refer to like parts in each of the figures.

The object of my invention is to provide an original shape for brushes; and to this end said invention consists in the design for a brush the leading feature of which is a handle shaped like a dumb-bell on the brush-back, substantially as herein shown and described.

In the drawings I show a brush A of oblong shape, on the back B of which is a handle that has a form similar to a dumb-bell—that is, the form of two suitably-spaced balls C and C, united by a connecting-piece C'. Between each ball and the brush-back is a neck-like part D, while at an opposite point on each ball is a rounded protuberance E.

Having thus described my invention, what I claim is—

The design for a brush, substantially as herein shown and described.

In testimony that I claim the foregoing I have hereunto set my hand this 1st day of April, A. D. 1899.

RACHEL LINDSLEY.
